UNITED STATES PATENT OFFICE.

IRVING B. SMITH, OF PHILADELPHIA, PENNSYLVANIA.

ELECTRICALLY-OPERATED MUSICAL INSTRUMENT.

1,168,755.

Specification of Letters Patent. Patented Jan. 18, 1916.

Application filed May 26, 1910. Serial No. 563,602.

To all whom it may concern:

Be it known that I, IRVING B. SMITH, a citizen of the United States, residing at Philadelphia, in the county of Philadelphia and State of Pennsylvania, have invented 5 new and useful Improvements in Electrically-Operated Musical Instruments, of which the following is a specification.

My invention relates to automatic playing 10 mechanism for musical instruments, and particularly to automatic playing mechanisms for use in connection with grand piances.

While particularly designed for use in 15 connection with grand pianos it will be readily seen upon reading the following description that my invention possesses many features which are applicable to other types of musical instruments, and that it may be 20 used in connection with certain other types of musical instruments practically in toto and without substantial change.

The application of automatic playing 25 mechanisms to grand pianos has been attended with considerable difficulty owing to a lack of space in a piano of this type, to the peculiarities of the piano action, and the peculiar arrangement of the parts of the piano. For these and other reasons it has 30 been difficult to get a playing mechanism applied to a grand piano which would operate in an efficient and entirely satisfactory manner without interference with manual operation of the piano which should be possible 35 whenever desired. Also due to the causes mentioned the application of an automatic playing mechanism to pianos of this type has detracted from their artistic, neat and attractive appearance and more than that 40 has been placed in a position in which it is decidedly in the way of the persons performing upon the piano.

It is one object of my invention to overcome the above named difficulties and to produce, adapt and apply an automatic playing 45 mechanism to grand pianos in such a manner that it will operate the piano and in turn allow the piano to be operated, manually, in an entirely satisfactory and reliable manner 50 and with excellent efficiency.

It is a further object of my invention to produce a playing mechanism for grand pianos which may be applied to any one of the different makes of grand pianos at will and 55 with a simple change of dimensions, and

without substantial alteration of any of its structural features.

In the accomplishment of my invention I make use preferably of an electro-magnetic playing mechanism for the reason that this 60 mechanism occupies a very small space and may be placed in very small compass. At the same time it operates simply and reliably. Other types of playing mechanisms may be used, but generally must occupy a 65 greater space. I mount this mechanism beneath the piano, attaching it to the key bed just below the hammer action, which in this type of piano is usually located in the front of the casing. In this position the playing 70 mechanism is readily accessible for adjustment of its parts, and for adjustment or removal of the mechanism as a body. I connect this mechanism to the hammer action by striker rods which I connect to elements 75 of the playing mechanism and pass through the key bed to engage the rear ends of the key levers associated with the hammer action of the piano.

The electro-magnetic mechanism which I 80 have produced and adapted to grand pianos possesses several advantageous features not heretofore found in playing mechanisms of this type. Prominent among these is an electro-magnetic means for decreasing the 85 power required to operate the mechanism and for increasing the rapidity of repetition possible in a playing mechanism of the automatic type. And to further the adaptability 90 of the playing mechanism and to secure minimum of interference with manual operation of the piano I make use of an improved phrasing bar designed to meet the demands for fineness of expression in this type of piano. As will be seen it is especially constructed to fit in with the remaining parts 95 of the piano, and to improve the quality of playing done by the automatic playing mechanism.

I show in the accompanying drawings a 100 specific embodiment of my invention.

Figure 1 is a sectional elevation along the lines of the key levers of a grand piano equipped with the automatic playing mechanism of my invention. Fig. 2 is a partial 105 section substantially on the line 2, 2, of Fig. 1 at right angles to the line of the key levers. Fig. 3 is a somewhat diagrammatic view of the rear ends of the key levers shown in Fig. 2, and showing the relation of these 110

rear ends of the key levers to the front ends, or so called the ivory keys. Fig. 4 is a perspective view of several elements of the electro-magnetic playing mechanism showing 5 their connection with the rear ends of the key levers. Fig. 5 is a vertical, longitudinal section through one of the elements of the playing mechanism. Fig. 6 is a detail sectional view of one of the striker rods connecting the actuating elements with the rear 10 ends of the key levers. Fig. 7 is a plan view of the under side of the improved phrasing bar which I have designed. Figs. 8 and 9 are plan and side elevations respectively of 15 one of the supports for the phrasing bar of Fig. 7. Figs. 10, 11 and 12 are detail views of joints in the phrasing bar. Fig. 13 is a plan view of the under side of operating arms, shafts and operating levers for the 20 phrasing bar. Figs. 14 to 17 are diagrammatic views showing four of the expression combinations possible with the aid of the phrasing bar of Fig. 7. Figs. 18 and 19 are enlarged, perspective views of forms of 25 metal clips suitable for extensions of the key levers, and Fig. 20 is a diagram of the electrical connection of the several elements of the electro-playing mechanism. Fig. 21 is a side view of a modified form of phrasing 30 lever; and Fig. 22 is a transverse section of a modified form of bar.

Referring to Fig. 1, 10 is the key bed of the piano above which are mounted the key levers 11. 12 designates collectively the 35 hammer action with which the key levers are associated and on which they act. 13 designates the damper mechanism, and 14 the sound producing elements or strings on which the hammer action and damper action 40 act. 15 is the electro-magnetic playing mechanism located beneath the key bed and acting on the rear ends of the key levers. 16 is the improved phrasing bar.

Speaking more specifically of the hammer 45 action, 19 is the wippen of the action which is engaged by the rear ends of the key levers. 20 is the repetition lever, 21 the hammer shank, 22 the hammer which strikes the strings 14, and 23 the back check. This 50 mechanism it is to be noted is mounted in the front of the piano adjacent the keyboard.

The electro-magnetic playing mechanism 55 comprises a plurality of actuating electro-magnets 24 disposed within the body of a bar of magnetic material 25 which forms the back-bone of the mechanism, and is disposed flatwise in a horizontal plane parallel to the key board. The bar is longitudinally parallel to the line of the rear ends of the key levers, see Fig. 2. This bar is supported at its ends by two brackets 26 which are hinged at one of their ends 27 to the key bed 10 and 60 removably secured thereto by the other ends 65 28. Intermediate its ends, and approxi-

mately at its center, the bar 24 is supported by a lag screw 29 passing through it and entering the bottom of the key bed.

Each element of the playing mechanism (see Fig. 4) comprises one of the electro-magnets 24, an armature therefor 30, which is hinged at one end to the bottom of the rail, and an actuating shoe 31 connected to the armature 30 by means of a saddle 32. The saddle 32 is of spring metal and is connected to the armature at its hinged or bottom end. At its front end it is provided with two overhanging branches 33 to which the shoe 31 is pivoted by means of a pintle 34. The bodies of the shoes extend across 30 the top of the bar 25, while the feet hang over the rear side of the bar and are supported on a felted angle shaped rest-rail 35 upheld by U-shaped springs 36 secured to the bar 25 by adjusting screws 37 which pass through both branches of the U.

The rear ends of the shoes are rounded and adapted to engage the rotating power shaft or taper roll 38 carried in bearings in the brackets 26 which support the bar 25 35 immediately to the rear of the ends of the shoes. When the electro-magnets 24 are energized they draw their armatures inwardly and project the actuating shoes 31 into contact with the taper roll 38. A series of adjustments are provided for determining the time, pressure and extent of this contact. The first of these is embodied in a retractile spring 39 for each armature, and means for adjusting it. Springs 39 are leaf springs 40 secured to the rear ends of the armatures. They are engaged at their ends by the eccentric heads 40 of adjusting screws 41 passed through a stop rail 42 supported in fixed relation to the bar 25 and in front of 45 it. By turning the screws 41 the springs 39 may be flexed to the desired degree and the desired tension placed upon the armatures 50. Adjustable stops 43 are also supported by the stop rail 42 and provided with felted heads 44 which engage the front faces of saddles 32 and limit the movement of the armatures away from the magnets, and hence determine the air gap. Adjustment of 55 the stops 43 also adjusts the normal space 100 between the bottoms of the shoes 31 and the taper roll 38. A third of the adjustments mentioned is a complex adjustment 105 accomplished by an adjusting stud 45 which passes loosely through the saddles 32, and is 110 screw threaded through the armature 30, and is adapted to bear at its inner end against an armature stop rail 46 secured to the top of the bar 25. On their outer sides 115 the screws 45 are provided with nuts 47 120 which engage the saddles 32. The stop rail 46 is formed with a plurality of tongues 48 at an angle to its main body which project 125 one into each space between the arms 33 of the respective saddles and the shoes 31 130

connected therewith. By turning the nuts 47 on the ends of the studs 44 without turning the studs, saddles 32 are adjusted with respect to the armatures 30, and an adjustment 5 of the actuating shoes 31 secured to the saddles to and from the taper roll 32 is thus obtained. When this adjustment is made the air gaps of the electro-magnets are altered, but these are easily adjusted, 10 if necessary, by manipulation of the stops 43. By turning the studs 43 an adjustment of the armatures with respect to the armature stop rail 46 is had, and the inner position of the armatures is thereby determined, 15 as is also the pressure with which the respective shoes 31 bear against the taper roll. The ends of the studs 43 are felted in order to avoid noise due to impact with the tongues 48 of the stop 46. By the use 20 of these several adjustments just described the time, pressure and extent of engagement of the respective shoes with the taper roll 48 may be regulated with great exactness and nicety. A number of spring supports 25 36 are provided for the angular felted rest rail 45 for the toes of the shoes, and by relative adjustment of these springs the shoes may be all positioned so that they normally rest with their toes in the same right line. 30 The elements of the playing mechanism are associated with the rear ends of the key levers of the piano by striker rods 49 which are hinged to the horizontal upper bodies of the actuating shoes 31 and engage at 35 their upper ends extensions 50 of the rear ends of the levers. These striker rods are made in two parts connected together by sleeves 51. The upper part is screw-threaded into the sleeve (see Fig. 6) and provided 40 with jam nuts 52 bearing upon the top of the sleeves for clamping the same with respect to the sleeve, after adjusting the overall length of the rods. The lower parts of 45 these rods are sweated into the lower ends of the sleeves and are provided with T-heads 53. These T-heads 53 are seated transversely of the upper bodies of the shoes 31 in felted sockets 54, and are normally held in these sockets by the bifurcated ends of 50 leaf springs 55 secured to the shoes. The striker rods may be readily disengaged by removing them laterally to pull them from beneath the springs and the ends of the springs are upturned to facilitate their replacement by insertion beneath the springs. 55 The striker rods pass through holes 56 in the key bed and are guided at their upper ends by clips 57 (see Figs. 2 and 4) affixed to the upper side of the key bed. 60 The extensions of the rear ends of the key levers are formed by metallic clips which are felted on their under sides for engagement with the ends of the striker rods which are headed and rounded as shown. These 65 clips are of the general form shown in Fig. 2, being somewhat Z-shaped. They are not, however, all of the same angularity, the engaging ends of the respective clips being off-set from the rear ends of the key levers varying distances. The reason for this is 70 the fact that breaks are necessary at intervals in the rear ends of the key levers in order to accommodate the hammer action to the variation in distance between the strings of the instrument. This is especially necessary when over-stringing is done in the bass. The elements of the playing mechanism constituted by the electro-magnets 24 and associated parts are evenly spaced from each end of the bar 25 toward the middle of 75 the bar, this spacing in a playing mechanism which I have built for a piano of standard make being about nine-sixteenths of an inch. The ends of the key levers are, therefore, extended and the ends of the extensions off-set with respect to the rear ends of the key levers (see Figs. 2 and 3) in order to suit the playing mechanism having evenly spaced actuating elements for a 80 grand piano in which there are breaks between the rear ends of the key levers. It is to be observed that in this embodiment there is a break between the regular spacing of the actuating elements of the mechanism adjacent the lag screw 29. This is provided for 85 the obvious purpose of permitting the supporting lag screw to be passed through the bar. Instead of the lag screw some other support might be used in the space between the actuating elements which is provided in 90 this manner. The provision of this space entails off-setting of the extensions of the rear ends of the key levers in the same manner as do the breaks above taken note of. 95 It is particularly desirable that the mechanism of this type should operate with a very small consumption of power, as it is possible with a mechanism using only a small amount of power to operate the same from primary or storage batteries. I have, 100 therefore, provided in connection with the damper mechanism of the piano a device for use in conjunction with the playing mechanism which materially decreases the power used, and in addition materially increases 105 the rapidity of repetition possible. 58 are the damper levers, Fig. 1, which are pivoted at 59 to their supports. 60 are the damper rods connected with the individual dampers 61. Just above each damper lever 58 is an 110 electro-magnet 62 arranged to act on an armature 63 carried by the damper lever. Each armature is felted on its engaging face or provided with a leather covering in 115 order to prevent noise during engagement. These magnets are connected respectively in parallel with the respective actuating magnets 24 of the playing mechanism, as clearly shown in Fig. 20. Secured to a support 64 and in operative relation to each damper rod 120 125 130

60 is a movable contact 65 coöperating with a fixed contact 66, and these contacts are in series in each instance with the corresponding electro-magnet 24 of the playing mechanism. An adjustable collar 67 on each damper rod actuates the movable contact 65 when the dampers are raised to open the circuit of the electro-magnets 24 at these contacts.

10 The operation with the addition of this device is as follows: When contact is made by one of the fingers 68 of the reader 69 (see Fig. 20) a circuit of one of the electro-magnets 24 and a corresponding electro-magnet 62 is closed. Immediately the actuating shoe of the electro-magnet 24 is drawn to the power shaft 38 and the shoe is thrown upward thus actuating the key levers associated with the hammer action and through 15 the key lever, the hammer to strike the string. Simultaneously the damper mechanism is actuated to lift the damper from the string. By this movement the circuit of the energized electro-magnet 24 is broken at the 20 corresponding contact 65, 66, by the upward movement of the damper. Immediately the actuating shoe which moved the parts returns to its normal position against the rest rail 35, and so does the actuated hammer of 25 the hammer action. But the damper is held up by the action of electro-magnet 62 on its armature 63, and the circuit including the corresponding electro-magnet 24 is held open at contact 65, 66, until the contact of 30 finger 68 with the reader 69 is broken. Upon the breaking of this contact electro-magnet 62 is deenergized and permits the parts to return to their normal positions. Electro-magnet 62 may be made of very 35 fine wire as it is required to exert but little power, and much power is therefore saved, as a comparatively great amount of power is required to operate the electro-magnets 24. Inasmuch as the actuating shoes drop 40 immediately back to their normal position after actuation, they are always ready to strike a second time, and to strike successively the same note a number of times.

In this connection I provide a second device for use when the device just described is not used, or for use in connection with it. This consists of a flange 70 depending from a bar 71 beneath the key bed and in the line of movement of the bottoms of the shoes. 50 This bar is provided with a plurality of spring tongues 73 one for each shoe, and each adjustable by a set screw 74 which passes through the bar 71. The heels of the actuating shoes upon energization of the respective magnets at the extreme end of their upward throw engage these tongues, the tongues being so adjusted, preferably, that they are engaged by the heels of the shoes only when the toe is past the taper roll and 55 the shoe has been moved bodily a slight dis-

tance toward the bar by its armature. Whenever the device first described is installed as a part of the playing mechanism, I prefer to omit the device last described. However, I may provide both of these devices in a single 70 instrument and so adjust the one when the other is in operation that that one is out of operation. For instance, I may readily break the circuits of the magnets 62 if it is desired to use the bar 71, or I may readily adjust the 75 tongues 73 of the bar so that they do not engage if it is desired to use the magnetic mechanism associated with the dampers. Used at the same time as the damper device, the bar 71 and its contiguous parts act to 80 prevent the armatures 30 from impinging on the magnet rail, and further simply act to hold the shoes up until the magnet-circuits are broken at contacts 65—66.

Fig. 22 is a view of a form of bar in 85 which the parts 73 are omitted, and heads 70' of wood, leather, or other similar material, are used on the screws.

To further the range of use of the playing mechanism and to attain the range of expression desirable, I divide the phrasing bar 16 up into sections 75 to 79 (see Fig. 7). These sections are supported by the ends of supporting levers 80 pivoted at points 81, above the hammer action. The supporting levers 90 80 each comprise a main body 82 and a depending portion 83 at an angle to the main body portion which passes edgewise between the shanks 21 of the hammers of the action and engages the phrasing bar beneath the 95 shanks. The sections of the phrasing bar are variously connected to these levers. The section 75 is riveted to each of two supporting levers 80, see Fig. 7. The section 76 is hinged to the supporting lever 80 on the 100 end of section 75; sections 76 and 77 adjacent are connected at their adjacent ends to a supporting lever 80 by a sliding connection of the pin and slot type (see Fig. 7); the sections 77 and 78 are similarly connected 110 to a supporting lever 80 at their adjacent ends. The lever 78 is hinged to the supporting lever 80 after the manner of supporting lever 76 (see Fig. 10), and the section 79 is riveted to two adjusting supporting 115 levers 80 as is section 75. Reference to Fig. 12 will show that the end of section 77 which is not provided with a hinged joint which will determine its plane, is provided on one end with two sliding pin connections 120 with the supporting lever 80 adjacent.

Associated with the end of each supporting lever on the other side of its pivot or fulcrum 81 from the phrasing bar 16 is a connecting rod 84 which passes in front of 125 the hammer action between the key levers and through the key bed to a point beneath it. Beneath the key bed (see Fig. 13) each of the connecting rods 84 connects with an operating arm 85, associated with an operat- 130

ing shaft. The two endmost connecting rods 84 at each end of the mechanism are connected in the one case to an operating shaft 86 and in the other case to an operating shaft 87, while the two intermediate connecting rods 84 associated with the intermediate supporting levers 80 are connected one to an operating shaft 88 and the other to an operating shaft 89. All of these operating shafts are journaled in brackets 90 beneath the frame. Spiral springs 91 secured to the key bed at one end and to short arms 92 on the shafts at the other end normally retain the phrasing bar in pianissimo position. Four levers 93, 94, 95 and 96 associated with the shafts project forwardly to the front edge of the key bed where they are provided with thumb and finger pieces 97 for convenient hand operation. These levers are each made in two parts *a* and *b*, the part *a* being loosely journaled on the shaft and the part *b* being slidably connected therewith and extensible relatively thereto, so that the levers may each be extended to the edge of the key bed or pushed back out of the way beneath it at will. The part *b* engages at its inner end (see Fig. 1) a projection or short lever 98 fixedly attached to the shaft and provided with an engaging lug 99. The adjacent ends of the parts *b* of the levers 93 to 96 and the projections 98 from the shafts are correspondingly beveled so that when the parts *b* are shoved inwardly the projections 98 are engaged, and the respective shafts to which they are attached are turned. By removing the screws 101, the lever ends may be entirely removed.

The levers pass through a frame 100 by which they are guided in their upward and downward movements. By moving any one of the levers, the supporting lever or levers 80 of the phrasing bar are moved through the respective rods or rod 84 and the corresponding sections of the phrasing bar adjusted. Thus the sections of the phrasing bar may be moved to occupy a number of positions. Four of these are shown in Figs. 14 to 17 and from these it should be evident that the tone of the instrument may be practically modified at will. Intermediate the ends of the phrasing bar the tone modulation is graduated from one point to another as clearly shown, and by choosing suitable combinations of positions of the sections of the bar substantially all modulations of tone desired may be had, and the automatic playing mechanism may be made to simulate or approach very closely to producing music of the quality produced by human touch.

Fig. 21 shows a modified form of phrasing lever, in which the two parts *a* and *b* are made readily separable as well as adjustable, by forming an open ended slot in the end of the part *b* and attaching it to part *a* by screws, as shown. By this provision the

levers may readily be adjusted as to length, and may as readily be removed without removing the screws 101, instead of being pushed in under the keyboard.

What I claim is:—

1. The combination of sound-producing elements, a hammer action, key levers, a key bed for said key levers, a magnet rail made of a single bar secured adjacent to the underside of said key bed including magnet coils located on the bar, actuating shoes actuated by said coils disposed adjacent to said coils and in close proximity to said bar, and striker rods connected by one of their ends with said shoes and detachable therefrom by a lateral movement, and extending up through said key bed, said rods having their other ends in position to strike and operate said key levers. 70

2. The combination of a casing, sound-producing elements including a hammer action and key levers contained therein, a frame work exterior to and below said casing and hinged thereon at one side, means on the other side of the frame work for removably securing it to the casing, a magnet bar carried in said frame, including magnets supported by said bar, armatures for said magnets pivotally mounted on said bar, actuating shoes each pivotally connected to an armature, and striker rods connected to said actuating shoes and extending into said casing in position to strike said key levers when the shoes are actuated, said striker rods being unconnected with the key levers. 90

3. The combination of a casing, a hammer action located therein, key levers for actuating said hammer action, striker rods for moving said key levers extending through the bottom of said casing, said key levers manually movable independently of said striker rods, said striker rods unattached to said key levers, mechanism for actuating said striker rods located on the exterior of the casing, a frame work carrying said mechanism pivotally attached under said casing to enable said frame work to swing down and away from the lower ends of said striker rods, and removable means for attaching said frame work to said casing to hold said frame work normally against said casing with said mechanism in operative connection with said striker rods. 105

4. The combination of a casing, sound-producing elements disposed within said casing, a hammer action located within said casing, key levers provided at their rear ends with clips extending in different directions, connections from said key levers to said hammer action, striker rods engaging said clips, and means operated automatically through the movement of a music sheet for actuating said striker rods. 120

5. The combination of a hammer action, key levers connected with said hammer 130

action for actuating the same, striker rods connected with said key levers and provided with T-shaped members, actuating shoes provided with openings for receiving said 5 T-shaped members, leaf springs mounted upon said actuating shoes and provided with portions engaging said T-shaped members to yieldingly hold them connected to said actuating shoes, and means for actuating 10 said shoes.

6. The combination of sound-producing mechanism, key levers, a casing containing said sound-producing mechanism, a magnet bar having a flat form disposed exterior 15 to said casing and near the rear ends of the key levers, said magnet bar being provided with magnets mounted thereupon, armatures therefor, actuating shoes pivoted on said armatures, means for actuating said shoes, 20 and connections between said shoes and the key levers for operating the key levers.

7. The combination of sound-producing elements, a hammer action, key levers, a plurality of actuating shoes each pivotally 25 mounted at one of its ends and free at its other end, means disposed adjacent said other end for swinging the actuating shoe upon its pivotal support, electro-magnetic mechanism for moving said actuating shoes 30 into frictional engagement with the swinging means, and striker rods each connected at one end with each actuating shoe and having its other end in position to operate a key lever, said key levers being manually 35 movable independently of said striker rods.

8. The combination of a magnet bar, means for supporting the same, a core, an armature pivotally mounted upon said magnet bar, an actuating shoe pivotally connected with said armature and movable thereby, a power shaft for engaging and swinging said actuating shoe when moved into engagement with said shaft by the said armature, a striker rod above and supported 45 by said actuating shoe at a point between said power shaft and the pivotal connection of said actuating shoe with the armature, and a key lever movable independently of said striker rod but adjacent said striker rod 50 to be moved thereby.

9. The combination of a casing, a hammer action located therein, key levers connected with said hammer action, a magnet bar having a flat form and disposed parallel 55 with the rear ends of said key levers, armatures hinged upon said magnet bar, actuating shoes pivotally mounted on the armatures and extending over the magnet bar, each shoe being provided with a portion extending 60 downwardly alongside of one edge of said magnet bar, a rest rail disposed adjacent said edge for limiting the travel of said actuating shoe in one direction, a power shaft for swinging said shoe in the oppo-

site direction, and operating means between 65 said shoe and said key levers.

10. The combination of a casing, a hammer action mounted therein, key levers for operating the hammer action, a key bed for said levers, a magnet bar having a substantially flat face and secured with said flat face adjacent and substantially parallel with the under side of said keybed under the rear ends of the key levers, said magnet bar including magnets, armatures carried by said 75 magnet bar and movable by the magnets, said armatures extending slightly above the surface of said magnet bar, actuating shoes pivotally connected with the upper portions of said armatures, a power shaft disposed 80 adjacent said actuating shoes adapted to engage and elevate the latter when said armatures are attracted by said magnets, and striker rods supported by said shoes extending upwardly therefrom through the key- 85 bed and terminating adjacent to said key levers to actuate the same, said striker rods permitting the manual movement of said key levers independently of said striker rods. 90

11. The combination of a casing, a hammer action located therein, a magnet bar disposed adjacent to said casing and exterior thereto, said magnet bar including magnets, armatures pivotally mounted at one end on 95 said magnet bar and controlled by the magnets, spring plates mounted upon said armatures at their pivotal ends and projecting at right-angles thereto, adjusting screws mounted in a fixed support and provided 100 with eccentric heads for engaging said springs to vary the tension thereof, actuating shoes pivoted on said armatures and movable bodily thereby, a power shaft for swinging said actuating shoes when brought 105 into frictional contact with said shaft, and connections from said actuating shoes extending into the casing for actuating said hammer action. 100

12. The combination of a casing, sound-producing elements, a hammer action, key levers mounted therein, actuating shoes for operating said key levers, striker rods supported by said actuating shoes extending upwardly therefrom and engaging the key 115 levers for moving said levers, movable armatures on which said actuating shoes are pivotally mounted, means for adjusting the movements of said movable armatures to limit the travel of said actuating shoes, and 120 a power shaft to be engaged by said actuating shoes when thus moved by said armatures. 115

13. The combination of a magnet bar with magnets carried thereby, armatures movable 125 relatively to said magnets, actuating shoes pivotally connected with said armatures, the bodies of said actuating shoes being dis-

posed above said magnet bar, while their feet portions extend downwardly behind the bar, a rest rail for said actuating shoes, resilient supports secured to the underside of said magnet bar and extending rearwardly therefrom to carry the rest rail, sound-producing elements, key levers, striker rods connected with said actuating shoes for moving the key levers, and a hammer action including hammers to strike said sound-producing elements, actuated by said striker rods.

14. In a piano, the combination of a casing, sound-producing elements, a hammer action, key levers for actuating said hammer action located within said casing, said casing comprising a keybed, a frame located without said casing and pivoted thereto at one side of said frame, means for removably securing the other side of said frame to said 20 casing, automatic playing mechanism supported by said frame, and striker rods having a connection with said automatic playing mechanism disengagable by a lateral movement of the striker rods, said striker rods 25 extending up through said keybed into said casing unattached to said key levers and in position to operate the key levers.

15. The combination of a casing, sound-producing elements within said casing, a 30 flat magnet bar disposed flatwise beneath the underside of said casing, magnets formed on said magnet bar, armatures for said magnets mounted adjacent the front lower edge of said magnet bar, actuating shoes pivotally 35 connected with said armatures and extending rearwardly over said magnet bar, a power shaft disposed adjacent to the free ends of said actuating shoes and adapted to be engaged thereby when said actuating 40 shoes are moved by said armatures, and striker rods for operating said hammer action connected with said actuating shoes at points located between the ends thereof.

16. An electromagnetic automatic playing 45 mechanism for pianos, comprising a magnet rail, magnets carried by said rail, armatures for said electromagnets, spring saddles on said armatures having parallel integral bearing arms, actuating shoes pivotally mounted 50 in the arms of said saddle to be moved longitudinally, a rotary power shaft for swinging the shoes, studs screw threaded through the armatures and passing through holes in said saddles, and nuts on said studs outside of the 55 saddles by which the saddles may be moved with respect to said armatures to adjust the shoes toward and from the shaft.

17. An electromagnetic automatic playing 60 mechanism for pianos, comprising a magnet rail, magnets carried by said rail, armatures for said electro-magnets, spring saddles on said armatures, actuating shoes pivotally mounted in said saddles, a rotary power shaft for swinging the shoes, studs screw

threaded through said armatures and passing through holes in said saddles, nuts on said studs outside of the saddles by which the saddles may be moved with respect to said armatures to adjust the shoes toward and from the shaft, and abutments on the rail opposite the inner ends of the studs, which studs may be turned independently of the nuts and without changing the adjustment of the saddles when necessary to adjust the engagements of said studs with said 75 abutments.

18. An automatic electromagnetic playing mechanism for pianos, comprising a magnet rail, magnets carried by said rail, armatures for said electro-magnets, actuating shoes 80 connected with said armatures, and a spring supported rest rail for said shoes in their normal rest position.

19. An automatic electromagnetic playing mechanism for pianos, comprising a magnet 85 rail, magnets carried by said rail, armatures for said electro-magnets, actuating shoes connected with said armatures, and a rest rail for said shoes in their normal rest position, and U-shaped bent springs which 90 support said rest rail, and are secured to the side of said magnet rail by screws which pass through both branches of the U and enter said rail.

20. In a piano, sound-producing elements, 95 a hammer action, keys for operating said action, an automatic playing mechanism comprising a plurality of actuating members, and striker rods connected to said actuating elements and engaging said keys, said 100 striker rods having portions seated in sockets on the actuating members, and resilient means for removably retaining said striker rods in said sockets.

21. In a piano, sound-producing elements, 105 a hammer action, keys for actuating the hammer action, an automatic playing mechanism therefor comprising a plurality of actuating members, sockets transversely located on the same, striker rods having laterally extending heads seated in said sockets, forked resilient fingers for removably retaining said striker rods in said sockets, said 110 striker rods also engaging said keys.

22. In a piano, sound-producing elements, 115 a hammer action, means for operating the hammer action, an automatic playing mechanism associated therewith, said mechanism comprising a plurality of actuating members, striker rods connected to said actuating members and bearing on elements of said operating means, said striker rods having T-headed lower ends seated in sockets on the actuating members, and spring retaining members which yieldingly hold said ends of 120 the rods in the sockets and permit easy inserting thereof and removal thereof.

23. In a piano, sound-producing elements,

- a hammer action, actuating means for the hammer action, an automatic playing mechanism associated therewith, said mechanism comprising a plurality of actuating members, striker rods connected to said actuating members and engaging said actuating means, T-heads on the lower ends of said striker rods seated in sockets in the actuating members, and spring retaining members 10 comprising flat springs secured at one end to said actuating members and having a free end overlapping the T-heads of said rods to removably retain them in the sockets.
24. In a piano, sound-producing elements, 15 a hammer action, operating means for the hammer action, an automatic playing mechanism associated therewith, said playing mechanism comprising a plurality of actuating members, and striker rods operatively 20 connecting said actuating members and said operating means, said rods comprising a stem, a sleeve portion threaded on said stem, a T-head fixed on the sleeve portion, and means for locking fast the sleeve and rod 25 portions after adjusting them with respect to each other.
25. In an automatic piano, a hammer action, key levers operatively engaged therewith and unevenly spaced at their rear ends, 30 extensions of different lengths on the rear ends of said key levers offset therefrom, the free ends of which are evenly spaced, and a playing mechanism the elements of which are evenly spaced, and evenly spaced connections between said key lever extensions and the playing mechanism elements.
26. In combination, in an automatic piano, 35 a hammer action, key levers operatively engaged therewith and unevenly spaced at

their rear ends, a playing mechanism the 40 elements of which are evenly spaced, and means connected to the key levers and extended therefrom in position to be engaged by the elements of the playing mechanism, 45 said means projecting in different directions to accommodate the uneven spacing of the key levers.

27. In a grand piano, sound-producing elements, key levers irregularly spaced at 50 their rear ends, a playing mechanism comprising a magnet rail containing a plurality of regularly spaced magnets, actuating members movable by said magnets for operating the key levers, and means including offsets from the rear ends of said key levers 55 alining with said magnets whereby the irregularly spaced key levers' ends may be operated from the regularly spaced magnets of the playing mechanism.

28. In an automatic piano, in combination, 60 a hammer action, a casing for said action, a magnet bar on the exterior of said casing, said magnet bar having a substantially flat face, said bar secured to the outer side of 65 said casing, with said flat face of said bar adjacent to and substantially parallel to the face of said casing, said bar having magnets, and connections between said magnets and said hammer action to actuate the same when 70 said magnets are energized.

In testimony whereof I have hereunto set my hand in presence of two subscribing witnesses.

IRVING B. SMITH.

Witnesses:

GEORGE L. RUBICANE,
BERNARD J. ARNDT.
